[57] CLAIM

The ornamental design for the necklace, as shown and described.

DESCRIPTION

FIG. 1 is a perspective view of a necklace showing my new design;

FIG. 2 is a front elevational view;

FIG. 3 is a rear elevational view;

FIG. 4 is a top plan view;

FIG. 5 is a bottom plan view;

FIG. 6 is a right side elevational view; and,

FIG. 7 is a left side elevational view.

The right and left sides of the necklace viewed from inside the loops appear, respectively, the same as FIGS. 7 and 6.
